[57] ABSTRACT

The invention is a circular billiard or pool table having a number of pockets or openings, for receiving billiard balls, which are equally spaced around a circular bumper. Spaced at a mid position between each pocket on the circular bumper is a flat bumper that projects inwards towards the center of the table to prevent billiard balls from traveling a path continuously along the curved bumper to a pocket and also to provide a limited flat bumper surface for rebounding balls.

CIRCULAR BILLIARD TABLE WITH CURVED AND STRAIGHT BUMPER SECTIONS

BACKGROUND OF THE INVENTION

The game of billiards or pool is most commonly played on a rectangular flat surface which is surrounded by a rectangular bumper and a plurality of ball pockets located in the bumper to receive a correctly moving ball. The rectangular tables, up to now, have received world wide use. Various other shapes have been explored to make for a more interesting game. A polygonal table was patented in U.S. Pat. No. 2,262,610, entitled "Billiard Table" by Harry Kellerman in 1941. The table disclosed in that patent was a deviation from the more common rectangular table. The pockets were positioned at each juncture of the sides of the polygonal. With this configuration no pocket was positioned opposite a flat bumper section so it was always necessary to rebound the ball at an angle into a pocket unless there was a direct shot which did not require the use of a bumper. The amount of skill necessary to play the game on such a table was thereby greatly increased making for a more interesting game.

A completely circular game table is disclosed in U.S. Pat. No. 2,361,471, entitled "Game Apparatus" by V.H. Fontaine Jr. which issued in 1944. In that patent there is disclosed a circular table which is rotatable so that people may sit while they play the game. When it is an individuals turn he simply rotates the table around to his position and takes his shot.

Another patent of interest for background purposes is U.S. Pat. No. 1,669,822, entitled "Game Apparatus" by Tresham D. Gregg issued in 1928. The game board of that patent is a convertible one. In one position the bumpers form a square table and with a flip of panels the table can be changed into a circular table having four pockets.

SUMMARY OF THE INVENTION

In the preferred embodiment of the present invention, a circular, flat, table is encircled with a circular bumper. Pocket means, openings, for receiving balls are positioned around the circumference of the bumper. A number of flat bumper surfaces corresponding in number to number of pockets are positioned on the circular bumper between each pocket projecting inward towards the center of the table. The composite bumper thus formed is comprised of alternate sections of curved and substantially flat surfaces. The inward projection of the flat bumper surfaces prevents a player from walking the ball along the curved bumper until it drops into a pocket. The flat bumper surface also permits angled rebound shots to be made similar to those made on the rectangular or square table. The present invention thereby embodies the best features of the flat cushion table with the best features of the circular cushion table.

Accordingly it is an object of the present invention to provide an improved billiard / pool table.

It is another object of the present invention to provide an improved billiard / pool table of the circular type.

It is another object of the present invention to provide an improved billiard / pool table having alternate curved and flat bumper sections.

It is another object of the present invention to provide a table on which balls are rebounded in to pockets on the table with the rebounding surfaces being flat and circular.

It is another object of the present invention to provide a circular pool table having substantially flat bumper surfaces extending inward from the circular bumper sections. This provides a flat surface for angular rebound shot from any place on the table to a pocket.

BRIEF DESCRIPTION OF THE DRAWINGS

FIG. 1 is a top view of a preferred embodiment of the table.

FIG. 2 is an enlarged section view taken along the section lines 2-2 of FIG. 1.

FIG. 3 is a projection view of the preferred embodiment of the invention.

DESCRIPTION OF THE INVENTION

Referring to FIG. 1, a circular pool, or gaming, table 10 is shown having a flat, circular, playing surface 11, which is surrounded by a ring side wall 15. The side wall 15 and the playing surface 11, each have a plurality of ball pockets (openings) 12, equally displaced around the periphery of surface 11.

Affixed to the inner surface of side wall 15 are curved bumper sections 14. Positioned at approximately the mid-position between each ball pocket 12, is a bumper 18 having a substantially straight horizontal surface 20, as compared to the surface of the curved bumper sections 14. The straight horizontal bumper surfaces 20 project inwards towards the center of the table 10. The length of bumper 18 is shorter than any section of curved bumper 14. In the embodiment shown, 6 straight bumpers are provided. Any number of straight and curved bumpers may be used to make the game more interesting.

Referring now to FIGS. 2 and 3. The straight bumper 18 is shown comprised of a solid wood section 25, covered along its edges with a rubber cushion 30. The straight horizontal surface (edge) 20 is connected to the curved bumpers 14 by means of two straight surfaces 22 and 24 which are canted at approximately 45° angles with respect to the straight horizontal surface 20. If the angle were 90° the playing balls could possibly be trapped in the formed corner.

The entire surface of the table including the bumper surfaces is covered with standard pool table felt, not shown for purposes of clarity to provide the proper playing surfaces.

To summarize, the invention is directed to a circular pool table having a plurality of substantially straight horizontal bumper surfaces projecting inward. The straight bumper surfaces forming a minor portion of the tables total bumper surfaces.

Many changes and modifications may be made in the lengths, widths diameters and numbers of straight bumpers which will still be within the teaching of this invention.

We claim:

1. A circular pool table comprising in combination:
  - a. a flat circular playing surface with a plurality of pockets around the periphery thereof;
  - b. a circular bumper surrounding said playing surface; and

- c. at least one straight inwardly projecting horizontal bumper surface located on said circular bumper between at least a pair of said pockets.
- 2. The invention according to claim 1 including a plurality of said bumper surfaces on said circular bumper.
- 3. The invention according to claim 1 wherein said pockets comprise openings defined in said circular playing surface and said bumper to receive playing balls.
- 4. The invention according to claim 2 wherein said straight horizontal bumper surfaces are positioned on said circular bumpers between said defined openings to prevent a played ball from rolling along said circular bumper into a defined opening.
- 5. The invention according to claim 1 wherein said straight horizontal bumper surfaces have a length less than any circular bumper.

- 6. The invention according to claim 1 wherein said at least one straight horizontal bumper surface is connected to said circular bumper by straight horizontal bumper surfaces which are positioned at an angle with respect to said straight horizontal bumper surface.
- 7. The invention according to claim 1 including a plurality of said straight horizontal bumper surfaces equally spaced apart on said circular bumper.
- 8. The invention according to claim 3 including a plurality of said bumper surfaces and wherein said openings and said straight horizontal bumper surfaces are equally spaced apart on said circular bumper and said circular playing surface.
- 9. The invention according to claim 8 wherein said straight horizontal bumper surfaces have a length less than the distance between two adjacent defined holes.
